UNITED STATES PATENT OFFICE

2,232,734

REDUCTION PRODUCTS OF THE MALE SEX HORMONES AND OF COMPOUNDS OF SIMILAR ACTIVITY AND A METHOD OF PRODUCING THE SAME

Walter Schoeller, Berlin, Germany, assignor, by mesne assignments, to Schering Corporation, Bloomfield, N. J., a corporation of New Jersey

No Drawing. Application February 23, 1935, Serial No. 7,830. In Germany February 24, 1934

22 Claims. (Cl. 260—397)

This invention relates to the production of new compounds of the cyclopentano dimethyl polyhydro phenanthrene series, known also as the etiocholane series (saturated and unsaturated) and including reduction products of the male sex hormones and of compounds of similar physiological activity or chemical constitution, and more particularly to diols of the general formula $C_{19}H_{30}O_2$ and to diketones of the general formula $C_{19}H_{28}O_2$ and to a method of producing the same.

It has been found that compounds of special physiological activity, or capable of conversion into compounds of high physiological activity, can be produced from the male sexual hormones and from compounds of similar physiological activity having a keto group in their molecule, by reducing said keto group to the corresponding secondary alcohol group. Whilst, for instance, the male sex hormone of the formula $C_{19}H_{30}O_2$ and the melting point 178° C., possesses an activity of about 150 γ for the capon unit, the product obtained therefrom by reduction has an efficiency of about 15 γ for the capon unit. Hence, an increase in effectiveness of several times the original value is attained by this process of converting the keto group into an alcoholic hydroxy group. Thus, this invention enables the production of highly active preparations of the type of the male sex hormones in a simple and convenient manner.

Said reduction is preferably carried out by first dissolving the product to be reduced in a suitable solvent, such as alcohol, whereupon the hormones is reduced, for instance, by the addition of metallic sodium, i. e. by means of hydrogen in statu nascendi.

One may also proceed in such a manner, that the solution of the hormone is caused to react with amalgamated aluminum foils in the presence of water, or by allowing catalytically activated hydrogen to act under suitable conditions, such as increased pressure, on the starting material, care being taken that the keto group only is reduced to the alcoholic hydroxy group without, however, complete reduction to the desoxo-product taking place.

As starting material not only the crystalline male sex hormone of the formula $C_{19}H_{30}O_2$ (I) may be used but also its unsaturated derivatives such as the dehydroandrosterones of the formula $C_{19}H_{28}O_2$ (II) and the like. It is immaterial from what kind of initial materials these compounds are produced or obtained, whether from animal or vegetable sources or by synthetic means. Thus, the crude extracts of the male sex hormones, as they are obtained, for instance, from urine, fluids of the human body, organs and the like can be converted by reduction into diols of a substantially higher physiological value.

Likewise, isomers of the male sex hormones $C_{19}H_{30}O_2$ and $C_{19}H_{28}O_2$, as they are obtained, for instance, according to U. S. application Serial No. 36,984, filed August 20, 1935, and issued as U. S. Patent No. 2,184,299, said compounds being keto cyclopentano dimethyl tetrahydro phenanthrols (III) or keto cyclopentano dimethyl dodekahydro phenanthrols (IV) may be subjected to the action of the above described reducing agents.

This invention, furthermore, contemplates also another way of transforming the male sex hormones and the like compounds into diols of higher physiological activity. According to this modification of my process the starting materials are first converted by oxidation into the corresponding diketones of the formula $C_{19}H_{28}O_2$ (V) and $C_{19}H_{26}O_2$ (VI). These diketones are of higher physiological activity than the hydroxy ketones used as starting materials.

The physiological activity of these diketones is still further enhanced if they are converted by reduction into the corresponding dihydroxy compounds of the formula $C_{19}H_{26}O_2$ (VII). The latter compounds are the same as those obtained by directly reducing the starting materials in the manner described above.

The oxidation may be carried out in the usual manner, i. e. with chromic acid at an ordinary temperature, but other oxidation agents may also be used, such as copper oxide, mercuric oxide and other similar substances.

Likewise the hydrogenation of the diketone is effected in the usual manner but consideration must be paid to the fact that there is a possibility of the formation of various isomeric modifications, and that the ratio in which the different isomeric forms are obtained is itself dependent upon the methods of reduction. In accordance with the rule of Auwers and Skita mainly the trans-modifications are formed by reduction in neutral and alkaline medium whilst on the other hand, in acid solution, the cis-modifications are obtained.

The following structural formulas indicate by way of example the configuration of certain of the compounds used as starting materials and of those obtained by the processes claimed:

Male sex hormone—androsterone and its isomer, a keto cyclopentano tetrahydro phenanthrol

II and IV.

10 Unsaturated male sex hormone=dehydro androsterone and its isomer, a keto cyclopentano dodekahydro phenanthrol

15 Diketone obtained from I and III

20 Diketone obtained from II and IV

25 30 35 40 45 50 55 60 65 70 75 Dihydrogenated male sex hormone and its isomers

The following examples serve to illustrate the invention without, however, limiting the same to them.

Example 1

1 gram of the crystalline male sex hormone of the formula $C_{19}H_{30}O_2$ (melting point 178°) is dissolved in 250 cc. of alcohol. $\frac{1}{2}$ gram of metallic sodium is added in small portions to the solution. When the metal is dissolved, the solution is boiled for half an hour, whereupon it is poured into ten times its volume of water, said aqueous solution being then extracted with ether. The ethereal solution is washed free from alkali, dried and evaporated. There remains an oily product intermingled with crystals yielding on further purification a crystalline colourless compound of the formula $C_{19}H_{32}O_2$ (VII).

Example 2

1 gram of a crystalline crude male sex hormone is dissolved in 200 ccm. of cyclohexanol and after addition of 1 gram of a previously reduced nickel catalyst, subjected to the action of hydrogen at 150° C. and a pressure of 35 atmospheres. When the hydrogenation is completed,

the reaction solution is freed from the catalyst, evaporated in a vacuum and the residue is extracted with ether. After evaporation of the ether a white crystalline product is obtained which, compared with the starting material, shows at least a five-fold increase in effectiveness.

Example 3

2.41 grams of keto cyclopentano dimethyl te- 10 tradekahydro phenanthrol (III) produced as described in U. S. Patent No. 2,184,299, are dis- solved in 450 ccm. of glacial acetic acid. To this solution there is added an amount of chromic acid corresponding to 1.5 atoms of oxygen where- 15 upon it is kept for one day at room temperature. The solvent is then evaporated. From the solu- 20 tion, which is concentrated by evaporation until crystallisation sets in, the diketone is precipi- tated in crystalline form by the addition of water. On recrystallisation from diluted alcohol a di- 25 ketone of the formula $C_{19}H_{28}O_2$ (V) is obtained in long needles of the melting point 129° C. The yield amounts to about 2 grams or approximately 30 80-85%. The optical rotation of the product is 35 $\alpha = +0.76^\circ, [\alpha]_D^{20} = 104.8^\circ$

2 grams of the diketone thus obtained are hy- 30 drogenated in glacial acetic acid solution under addition of hydrogen bromide with hydrogen in the presence of platinum as catalyst. The solu- 35 tion is filtered off from the catalyst, poured into water and extracted with ether. After washing the ethereal solution with water and soda solu- 40 tion and evaporating, the hydrogenation product is isolated and can be purified by recrystallisation. The pure product (VII) has a many times higher 45 physiological efficiency than the starting ma- 50 terial.

Example 4

In a manner similar to that described in Ex- 55 ample 1, the keto cyclopentano dimethyl dodeka- 45 hydro phenanthrol, as obtained according to U. S. 60 Patent No. 2,184,299, can be converted by oxida- 65 tion into the corresponding unsaturated diketone of the formula $C_{19}H_{28}O_2$ (VI) which on hydro- 70 genation yields the same hydrogenation product (VII) as is obtained according to Example 1.

Of course, various modifications and changes 75 in the reaction conditions, etc. may be made by those skilled in the art in accordance with the principles set forth herein and in the claims annexed hereto.

What I claim is:

1. A method of improving the physiological ac- 80 tion of keto-containing male sex hormones of the general structural formula

the dotted line indicating the probable position of the double bond in the unsaturated hormones, comprising subjecting the starting material to the action of agents capable of reducing the keto group to the secondary alcohol group and of saturating a double bond when present, whereby

compounds of the general formula $C_{19}H_{32}O_2$ corresponding to the structural formula

are obtained.

15 2. A method as claimed in claim 1, wherein the starting material is subjected to the action of catalytically activated hydrogen.

3. A method as claimed in claim 1, wherein reduction is effected by means of nascent hydrogen.

20 4. A method of improving the physiological action of male sex hormones of the general structural formula

the dotted line indicating the probable position of the double bond in the unsaturated hormones, comprising treating the starting material with an oxidizing agent capable of converting the hydroxy into a keto group, and subjecting the diketone obtained thereby to the action of agents capable of reducing the keto groups to secondary alcohol groups and of saturating the double bond when present, whereby compounds of the general formula $C_{19}H_{32}O_2$ corresponding to the structural formula

55 are obtained.

5. A method according to claim 4, wherein the selective formation of the various isomeric modifications of the reduction products is effected by carrying out the reduction in alkaline, neutral or acid solution.

6. A method of producing reduction products of keto cyclopentano dimethyl phenanthrols of the general formula $C_{19}H_xO_2$, where x is 28 or 30 and corresponding to the structural formula

75 the dotted line indicating the probable position

of the double bond in the unsaturated compound, comprising subjecting the starting material to the action of agents capable of reducing the keto group to the secondary alcohol group, said reduction products having the general formula $C_{19}H_{32}O_2$ and corresponding to the structural formula

7. A method of producing reduction products of keto cyclopentano dimethyl dodekahydro phenanthrols of the general formula $C_{19}H_{28}O_2$ corresponding to the structural formula

comprising subjecting the starting material to the action of agents capable of reducing the keto group to the secondary alcohol group and of hydrogenating the double bond in the molecule of said starting material, said reduction products having the general formula $C_{19}H_{32}O_2$ and corresponding to the structural formula

8. A method of producing reduction products of keto cyclopentano dimethyl phenanthrols of the general formula $C_{19}H_xO_2$ where x is 28 or 30, and corresponding to the structural formula

the dotted line indicating the probable position of the double bond in the unsaturated compound, comprising subjecting the starting material to the action of an oxidizing agent capable of converting the hydroxy group into a keto group, and subjecting the diketone obtained thereby to the action of an agent capable of reducing the keto groups to secondary alcohol groups and of saturating a double bond when present, said reduc-

4

tion products having the general formula $C_{19}H_{32}O_2$ and corresponding to the structural formula

9. A method of producing reduction products
15 of keto cyclopentano dimethyl dodecahydro phenanthrols of the general formula $C_{19}H_{32}O_2$ corresponding to the structural formula

comprising subjecting the starting material to
30 the action of an oxidizing agent capable of con-
verting the hydroxy group into a keto group, and
subjecting the diketone obtained thereby to the
action of agents capable of reducing the keto
groups to secondary alcohol groups, and of hy-
drogenating the double bond in the molecule of
35 said starting material, said reduction products
having the general formula $C_{19}H_{32}O_2$ and corre-
sponding to the structural formula

10. A method of producing diketo cyclopentano tetradekahydro phenanthrenes of the gen-
50 eral formula $C_{19}H_{28}O_2$ corresponding to the struc-
tural formula

comprising subjecting keto cyclopentano tetradekahydro phenanthrols of the general formula
 $C_{19}H_{30}O_2$ corresponding to the structural formula

75 to the action of an oxidizing agent capable of

transforming the hydroxy group in said starting
material into the keto group.

11. Diketones of the general formula $C_{19}H_{28}O_2$ and the structural formula

12. A dialcohol of the general formula $C_{19}H_{32}O_2$ and corresponding to the structural formula

13. A method of producing 3,17 dihydroxy 30 cyclopentano dimethyl polyhydro phenanthrene compounds of the general formula $C_{19}H_{32}O_2$ and corresponding to the structural formula

45 which comprises hydrogenating a cyclopentano (13,14) dimethyl (10,13) polyhydro phenanthrene compound of the general formula $C_{19}H_{32}O_2$, wherein X is an even number from 26 to 30 inclusive, and at least one of the oxygen atoms is ketonic, to the saturated diol condition, and isolating the hydrogenated compound.

14. In a method of producing 3,17 dihydroxy cyclopentano dimethyl polyhydro phenanthrene compounds of the general formula $C_{19}H_{32}O_2$ and corresponding to the structural formula

7 the step which comprises hydrogenating a diketo (13,17) cyclopentano dimethyl (10,13) polyhydro phenanthrene compound of the general formula $C_{19}H_{28}O_2$, and recovering the hydrogenated compound.

15. In a method of producing 3,17 dihydroxy cyclopentano dimethyl polyhydro phenanthrene

compounds of the general formula $C_{19}H_{32}O_2$ and corresponding to the structural formula

compounds of the general formula $C_{19}H_{32}O_2$ and corresponding to the structural formula

5

5 the step which comprises hydrogenating an unsaturated diketo (13,17) cyclopentano dimethyl (10,13) polyhydro phenanthrene compound of the general formula $C_{19}H_{26}O_2$, and recovering the hydrogenated compound.

16. Cyclopentano (-13,14) dimethyl (-10,13) polyhydro phenanthrene compounds of the general formula $C_{19}H_{n}R_2$, wherein n is an even number from 26 to 28, and the two R's occupy the 3- and 17-positions, both being $=O$ when H is 26 and both being the same member of the group consisting of $=O$ and

when n is 28.

17. A method of producing 3,17 dihydroxy cyclopentano dimethyl polyhydro phenanthrene

5

10

which comprises hydrogenating a cyclopentano (13,14) dimethyl (10,13) polyhydro phenanthrene compound of the general formula $C_{19}H_{30}O_2$, 15 wherein one of the oxygen atoms is ketonic and is in the 17-position, and the other forms part of a hydroxyl group, to the diol condition, and isolating the hydrogenated compound.

18. A method according to claim 4, wherein 20 the selective formation of the various isomeric modifications of the reduction products is effected by carrying out the reduction in acid solution.

19. A method according to claim 4, wherein 25 the selective formation of the various isomeric modifications of the reduction products is effected by carrying out the reduction in alkaline solution.

20. A method according to claim 4, wherein 30 the selective formation of the various isomeric modifications of the reduction products is effected by carrying out the reduction in neutral solution.

21. Trans-androstandiol.

22. Cis-androstandiol.

WALTER SCHOELLER.
